UNITED STATES PATENT OFFICE

EDWARD E. GOLD, OF BROOKLYN, NEW YORK.

CAR-HEATER.

SPECIFICATION forming part of Letters Patent No. 242,299, dated May 31, 1881.

Application filed February 24, 1881. (No model.)

To all whom it may concern:

Be it known that I, EDWARD E. GOLD, late of New York city, but now a resident of Brooklyn, Kings county, New York, have invented 5 certain new and useful Improvements in Car-Heaters, of which the following is a specification.

The means heretofore employed for heating railway-cars, as is well known, are mainly of 10 three types—first, stoves located in the ends of the cars; secondly, special stoves organized to heat a circulating hot-water coil which extends from the stove along the floor of the car and is looped into lateral bends under the seats; 15 thirdly, steam-pipes coupled from car to car of the train and supplied from the engine, to which latter class my improvement belongs.

Stoves have one advantage in that they tend 20 to ventilate the cars, as well as heat them, but are defective in that they confine this heating and ventilating too much in certain parts of the car and do not secure an even diffusion thereof throughout the car; but their most serious objection is that in case of accident or 25 overturning of the car their coals are liable to become scattered and to set fire to the car, which is well known to be a most serious danger and a great cause of loss of life in railway accidents. While this latter objection applies 30 equally to both classes of stoves mentioned, yet the water-coil stove is a great improvement over the common stoves in effecting a diffusion of the heat throughout the car, yet is in turn defective in that the ventilation is not diffused 35 equally with the heating, and for the further reason that the heat is circulated in an unbroken water-circuit, and can hence be increased or reduced only at its source, (the stove,) and will then be increased or reduced uniformly 40 throughout the car, which may be insufficient for some passengers and too much for others.

The steam-heating system referred to as heretofore adopted has been applied chiefly to cars intended for transient travel and having 45 seats arranged lengthwise in each side of the car, and the steam-heating pipe has hence been arranged lengthwise of the car under the seats and inclosed in a casing or larger pipe filled with sand to diffuse the heat, the ends of this 50 steam-pipe being prolonged under the platforms and coupled from car to car and sup-

plied with exhaust or live steam from the engine. In this case, however, no means have been provided for apportioning the heat to any one seat or portion of the car independent 55 of any other portion, and no means of ventilation in connection with the heater-pipes has been provided.

One of the common objections to all steam-heating as usually conducted is the deadness 60 of the heating effect, as the air is simply heated without being renewed or the apartment ventilated by the heating action, which is very objectionable. Another difficulty found with the steam-heating of cars has been the freez- 65 ing of the water of condensation in the external parts of the steam-pipe or in the couplings between the cars.

My invention aims to so improve the steam-heating of cars as to enable the heat to be distributed independently to each seat and there apportioned or regulated to suit the passenger without affecting the heat in other parts of the car, and it contemplates more particularly 70 seats arranged transversely of the car, and further aims to secure an effective and distributed 75 ventilation throughout the car, whereby the air shall be both warmed and renewed; also to prevent the clogging of the pipes by frozen water of condensation.

To these ends my invention consists in the combination, with a car having transversely-arranged seats, of a main steam-pipe arranged longitudinally in the sides of the car, in combination with lateral independent branches extending therefrom under the several transversely-arranged seats, with means of regulating or apportioning the supply of heat from said main-pipe to said branches, whereby the heat at any one seat may be raised, lowered, 85 or entirely shut off without affecting the heat at other seats or the flow of heat through the main pipe to the next car.

My improvements also include small air flues or shafts in or on the sides of the cars at one 90 or more points arranged over said main steam-pipe, or inclosing a branch pipe rising therefrom into said flue, whereby a draft is established to draw the vitiated air from the car, and thus effect the ventilation thereof simultaneously with the heating.

The improvement further consists in auto-

matic traps arranged upon the drooping part of the main steam-pipe at the coupling between the cars, whereby the water of condensation is removed as fast as formed, and in the most effective manner to avoid freezing and clogging of the pipes.

My invention also consists in certain details of construction, as hereinafter fully set forth.

Figure 1 of the annexed drawings presents 10 a fragmentary side elevation of an ordinary railway passenger-car, having a part of one side broken away to show the interior. Fig. 2 is a 15 sectional plan of a portion of the car, clearly showing the arrangement of the steam-heating pipes in relation with the seats of the cars. Fig. 3 is a cross-section of one-half of the car; Fig. 4, a similar view, showing a modification, and Fig. 5 an enlarged detail view of one of the branch heaters. Fig. 6 is an enlarged 20 detail view of the coupling and trap; and Fig. 7, a sectional detail view, showing the manner of applying steam-pipes to new cars.

The body of the car is presumed to be of the usual construction, and hence requires no 25 description; and it may be observed that the seats *a a* are arranged in parallel transverse order, as usual in cars intended for long travel, the seats being extended from each side of the car, with a central aisle between the two rows in 30 the usual manner, as illustrated.

Along each side of the car, and near the floor thereof, is arranged a main steam-pipe, *b*, which pipe is preferably of one and one-half inch in diameter. Each end of this pipe makes a lateral bend or turn in the corners of the car, as 35 shown best in Fig. 2, and thence extends downward through the floor, passes under the platform and is terminated with a drooping section of flexible rubber pipe, *c*, which is terminated 40 with a suitable union or coupling, *d*, which couples to a similar construction on the next car. The main steam-pipe of one car is thus connected with the main pipe of the next, the initial end of the series being of course supplied 45 from the boiler of the engine, or from any other suitable source, with either live or exhaust steam—preferably the former. In case of live steam the terminal end of the steam-pipe on the last car will be closed by a trap, but in 50 case of exhaust-steam the end will be left open to avoid back-pressure. It may now be noted that each side of the car is supplied with a distinct steam-pipe, so that the steam is sent out 55 from its source in two streams, one on either side of the train, so that if the pipes on one side of the train should become inoperative from any cause the heat from the opposite side will suffice to warm the cars.

A series of distinct lateral branches or radiators, *E*, corresponding in number to the seats, project at right angles from the main pipe *b* and extend lengthwise under the respective seats, terminating at the aisle end thereof, as 60 fully shown in Figs. 2, 3, and 4. These branches or radiators are placed in recumbent or horizontal position, parallel with the car-floor or

nearly so, but slightly higher at the aisle end, so as to insure a drainage of the water of condensation back into the main pipe. These branches may be constructed in any suitable 70 way, but I prefer to make them, as shown best in Fig. 4, of a bent or U-pipe, *e*, having each leg opening into a double T, *g*, on the main pipe, while the looped part is inclosed in a sealed casing or large pipe, *h*, filled with some 75 non-freezing or slowly-freezing liquid—such as brine, glycerine, and water, &c. Each leg of the U-pipe where it opens from the main is provided with a valve, *f*, whereby the flow of heat into the branch may be regulated as desired, or shut off completely. In using exhaust steam these valves need not be employed.

The main pipe *a* being one and one-half inch in diameter, the U-pipe *e* is preferably one-fourth inch, and the casing *H* is preferably 80 made of pipe three inches in diameter, having its ends closed by screw heads or caps *i i*, through one of which the legs of the U-pipe project and are tightly secured therein by taper screw-bushings *k k*, as shown in Fig. 4. This 85 proportion of parts is not of course essential, but it is practically good, and, as will be observed, reduces each radiator to a small and compact size, whereas radiators are usually made too large for the space to be heated, causing 90 the space to become unbearably hot before the occupant is aware of it. This cannot occur in my improved car-heater, as all the radiators are made quite small, yet distributed to each seat of the car, so that the heat is 95 well diffused in a pleasant effective warmth throughout the car. Yet the local heat at the heater of each seat is sufficiently strong to make an effectual foot-warmer, for it will be observed on reference to Figs. 1 and 2 that 100 each heater is placed centrally beneath or a little eccentric to the seat, so as to conveniently serve as a foot-warming rest for the passengers on the seat next behind. The casing *h* surrounding the steam U-pipe *e* absorbs the 105 heat thereof and radiates it gradually outward, and it has the effect, so to speak, of diluting the heat and radiating it from a larger surface, which gives an equal warmth, but in a 110 diffused manner, and prevents the contact of 115 the air of the car with very highly heated surfaces, as would be the case were the pipe uninclosed, which would in a measure injure the healthful quality of the air.

According to my system it is designed that 120 that the branches *E* only shall act to heat the interior of the car, the main pipe *b* not being designed to radiate heat into the car at all, but merely to convey the heat from car to car, and to each of the branches in the cars, 125 and as the flow of heat into all of these branches is controllable, the temperature may always be kept at a pleasant degree within the car, and localized to suit the passengers at each seat, being thus an important improvement 130 over former heaters, and especially adapted for long travel. In order therefore to prevent

the main pipe from radiating its heat into the car it may be well covered by non-conducting material, as shown at *b'* in Figs. 3 and 5; but when the main pipe is arranged under a base-board, *l*, as shown in Fig. 4, or in the walls of the car, as shown in Fig. 7, the heat radiating from it passes up the ventilating-flues *n* and does not heat the interior of the car. Thus it will be seen that the main steam-pipes will never 50 disturb the easy regulation of the heat in each car and at each seat. Furthermore, the main steam-current will thus be kept quite hot as it should be in its flow from car to car, and all the water of condensation may be collected, 15 trapped, and discharged from each branch of the double T's *gg*, which will be very effective in preventing all clogging or freezing of the pipes even in very cold weather, as by this means the main part of the water of condensation will be taken from the interior of the car, where it cannot freeze, even under the most unfavorable conditions.

Besides distributing the heat throughout the car in a manner whereby it may be easily 25 regulated or localized in any part of the car, as just described, my system also includes means for renewing the air, or ventilating the car in a similar distributed manner simultaneously with the heating. To do this, instead 30 of covering the main pipe with non-conducting material, it may, in the construction of new cars, be placed between the inner and outer casings of the wall of the car-body, which will thus not only inclose the pipe in a protecting 35 air-jacket, so to speak, but the pipe will heat the air in this space, and thus tend to produce a draft between the casings of the car-sides, which may be utilized for a most effective distributed ventilation by making internal openings near the floor of the car through the inner 40 casings, and external openings through the outer casings near the roof of the car. (See Fig. 3.)

In old cars the main pipe may be inclosed along its length by a base-boarding, *l*, as shown 45 in Fig. 4, which may be perforated to admit air to the space between the casings, so as to produce a draft which will draw the vitiated air from the bottom of the car up between the casings and out through the same at the top, 50 which air will be replaced by pure air entering by the innumerable crevices of doors and windows, thus renewing the air gradually and continuously at all parts of the car, yet in so well diffused a manner as to produce no sensible 55 draft. In the practical application of my heater, however, to existing cars, I prefer to arrange the main pipe as shown in Figs. 1, 2, and 3 of the drawings, and protect it with non-conducting material; and at certain points 60 along the side of the car I extend a vertical branch, *m*, therefrom, preferably a U-pipe, as shown in Fig. 1, into a vertical flue or shaft, *n*, in or on the side of the car, which opens from the interior of the car near the floor, and 65 also at the top, if desired, by means of a register, and discharges outwardly through the

roof, as fully shown in Figs. 1 and 3, thus producing the desired ventilation in a simple and effective manner, as before described. Ordinarily the hollow space in the car sides between the windows may be utilized for these flues, as shown in Figs. 1 and 3; but when this is not the case a special flue of sheet metal or thin wood may overlie the inner casing between the windows, but being otherwise substantially 75 the same as illustrated, as regards relative arrangement and operation.

The main pipe *b* preferably inclines from the middle of the car toward each end, so that the condensation gravitates to the external ends 80 of the pipe, and at the drooping end of the coupling-pipe *c*, or rather on the coupling *d* itself, which is necessarily the lowest part of the main-pipe and the part most exposed to the cold, I attach an automatic trap, *F*, which 85 removes this water of condensation as fast as it accumulates, and before it can be chilled or frozen. These main traps, thus arranged on the couplings, will, it is believed, be sufficient 90 to keep the main-pipe free from any accumulated water of condensation, and minor traps on the T's *g* of the main pipe within the car, (not shown,) as before referred to, will not be required; but both may be used, if desired, for more certain efficiency.

I prefer to use a trap of well-known form, as shown best in Fig. 5, in which the water-ejecting tube *o*, which opens at one end into the coupling *d*, opens at the opposite end against a flexible metal diaphragm, *r*, forming the bottom of a cell, *s*, charged with a highly-volatile fluid. Hence when the pipe is clear of water the steam will come in contact with the diaphragm, and its heat will thus vaporize the volatile fluid and expand the diaphragm 100 against the orifice of the tube *o*, so as to keep the same closed and prevent the escape of steam. When, however, any water of condensation accumulates this will be forced by the steam against the diaphragm, and, being 105 colder than the steam, will cause the volatile fluid to cool and the diaphragm to contract away from the orifice, thus allowing the water of condensation to escape till the steam again strikes the diaphragm, when it will expand and close the orifice. This trap is 110 preferably turned on its side and extended laterally from the coupling, and is supported by a pendent arm, *t*, from the car-platform, to allow the coupling the necessary swing in turning 115 curves.

In lieu of charging the casings *h* with a liquid a solid of some kind may be used; but a liquid is preferable, as it insures a better circulation and diffusion of heat.

It may now be appreciated that my improved car-heater is peculiarly adapted for large cars intended for long travel, particularly sleeping and drawing-room cars, which are at present imperfectly ventilated, as it insures a 125 pleasant diffused warmth, together with a corresponding ventilation, and enables the same 130

to be regulated in any part of the car, thus rendering each seat or berth in one car independent of the others, and one car independent of the other cars, while it uses the steam in the most economical manner, as is necessary where the steam is supplied from the engine, and at the same time insures the certain removal of the water of condensation to keep the pipes in operative condition.

10 I am aware that it is not new to cover the main pipes of steam-heating apparatus with non-conducting casings, and also that main pipes with branches have been used in cars, and therefore I do not broadly claim such constructions.

15 What I claim is—

1. The combination, with a railway-car having transversely arranged seats, of a main steam-pipe arranged lengthwise of the car, and supplied at its initial end with steam from the engine or other source, and left either closed or open at its terminal end, with a series of distinct lateral branches extending therefrom corresponding to the seats and disposed lengthwise beneath the same, each of said branches being supplied with separate cocks, whereby the heat is supplied to each seat independently of every other seat, substantially as herein shown and described.

2. The combination, with a railway-car constructed with an air flue or passage in its walls opening interiorly and exteriorly, of a heating-pipe projecting into said flue and having both its ends communicating with the main heating-pipe of the car, substantially as and for the purpose described.

3. The combination, with a railway-car, of a vertical flue, *n*, in or on the walls thereof, with internal and external openings, the main heating-pipe *b* and a vertical branch, *m*, rising therefrom into said flue and having both its ends communicating with the main heating-pipe, and arranged and operating substantially as herein set forth.

4. The combination, with a railway-car provided with steam-heating pipes adapted to be

coupled from car to car and supplied from the engine or other source, of a trap arranged upon the external drooping portion of the main steam-pipes at the coupled ends between the cars, substantially as and for the purpose set forth.

5. In combination with a main steam-pipe running through a car and coupled from car to car, and constructed and arranged, substantially as described, to radiate little or no heat into the car, of a series of distinct lateral branches connected therewith and disposed lengthwise one under each seat of the car, each of said branches being supplied with separate regulating devices, whereby the heat can be regulated at any seat or cut off from one car without reducing the heat in the next, substantially as specified.

6. The combination, with a railway-car, of the main steam-pipe *b*, arranged longitudinally thereof, the transversely-arranged seats *a a*, and lateral steam-branches extending from said main pipe lengthwise beneath each of said seats, with casings *h*, sealed at both ends, surrounding said branches, substantially as and for the purpose set forth.

7. A heating apparatus for railway-cars, consisting of the main steam-pipe *b*, U-shaped branches *e*, opening laterally therefrom, casings *h*, sealed at both ends, inclosing said branches, and valves *f*, controlling the supply to said branches, substantially as herein shown and described.

8. In combination with a car provided with separate heating-pipes under each seat, a main steam-pipe connected with said heating-pipes and passing through the car in a separate chamber divided from the interior of the same, said chamber communicating with the ventilating-flues of the car, substantially as and for the purpose specified.
